CLAIM

The ornamental design for a wrist support for a keyboard, as shown and described.

DESCRIPTION

FIG. 1 is a top, front and end environmental perspective view of a wrist support for a keyboard showing our new design, the portion of the figure shown in broken lines representing a keyboard and user's hands and forming no part of the claimed design;

FIG. 2 is a top, rear and end perspective view thereof;

FIG. 3 is a top plan view thereof;

FIG. 4 is a bottom plan view thereof;

FIG. 5 is an end elevational view thereof, the opposite

end being a mirror image;

FIG. 6 is a front elevational view thereof; and,

FIG. 7 is a rear elevational view thereof.
